United States Patent Office.

WILLIAM WEILER, OF WASHINGTON, NEW JERSEY.

Letters Patent No. 80,579, dated August 4, 1868.

IMPROVED ROCK-DRILLING MACHINE.

The Schedule referred to in these Letters Patent and making part of the same.

TO ALL WHOM IT MAY CONCERN:

Be it known that I, WILLIAM WEILER, of Washington, New Jersey, have invented certain Improvements in Portable Rock-Drilling Machines; and I do hereby declare the following to be a full, clear, and exact description of the same.

My invention relates to certain improvements in the rock-drilling machine for which Letters Patent were granted to me on the 31st day of March, 1868, and it consists—

Firstly, of a driving-shaft, provided, at its opposite ends, with wheels of equal diameter, upon which the machine can be transported from place to place, the said driving-shaft being arranged to slide longitudinally in its bearings, so that it may be thrown in or out of gear with the mechanism which operates the drill.

Secondly, of a yoke, so secured to the top of the frame of the machine as to afford a ready means of attachment to the chain or rope by which the machine is shifted from one point to another.

In order to enable others skilled in the art to make and use my invention, I will now proceed to describe its construction and operation, reference being had to the accompanying drawing, which forms a part of this specification, and in which—

Figure 1 is a front elevation of sufficient of a rock-drilling machine to illustrate my improvements.

Figure 2, a rear elevation of the same.

Figure 3, a sectional plan view on the line 1-2, fig. 2.

Figure 4, a plan view of fig. 1, and

Figure 5 a view of the machine when prepared for transportation.

Similar letters refer to similar parts throughout the several views.

The frame of the machine consists of a base, A, and of four uprights, B, B¹, B², and B³, which project from the base, and are secured together at the top, and braced, throughout their length, by cross-pieces, a.

Around each of the uprights, near to the top of the same, passes a metal band, b, between the projecting ends of which is hung a leg, C, somewhat longer than the upright to which it is hinged, the lower ends of the legs projecting outwards from the frame of the machine, as clearly shown in fig. 2. These legs are hinged to the uprights by pins, d, in such a manner as to be easily detachable therefrom, and they afford a ready means of supporting the frame of the machine in any position in which it may be placed, enabling me to dispense with the inconvenient extended base described in my aforesaid patent of March 31, 1868.

The driving-shaft D of the machine is arranged to turn in suitable bearings, f f, of the opposite uprights B² and B³, and to have a limited longitudinal motion through the said bearings, for a purpose described hereafter; and the said shaft is provided with a cog-wheel, g, gearing into a similar wheel, g', at one end of a shaft, E, which also turns in the opposite uprights B² and B³.

This shaft E is provided with band-wheels, &c., (not shown in the drawing, but fully described in my former patent,) by means of which motion is communicated to the drill-rod and its appliances.

Upon the opposite ends of the driving-shaft are wheels, F F, of equal diameter, which serve the twofold purpose of fly-wheels and as a means of transporting the machine from place to place, when the latter is turned over on to its side, as shown in fig. 5. Before thus turning the frame of the machine, however, it is necessary that two or more of the hinged legs C should be detached, which is readily done after withdrawing the pins d. It is also necessary, in order to prevent injury to the machinery, that the cog-wheel g of the driving-shaft should be thrown out of gear with the wheel g'. This is done by sliding the driving-shaft longitudinally in its bearings to the position shown in figs. 1 and 4, and the shaft is maintained either in this, or in its former position, by means of a pin, i, which passes through a staple, i', secured to the cross-piece a', and bears against one side or the other of a collar, j, of the shaft. In some instances, however, the shaft E, or one of the cog-wheels g g', may be arranged to slide laterally, instead of the shaft D.

A yoke, G, which is secured to the top of the frame of the machine, affords a ready means of attachment to a crane, when it is desired to lift and move the machine from one point to another in the quarry, or of attaching it to a team or wagon when it is to be moved from place to place.

In my aforesaid patent of March 31, 1868, the drill-rod L was guided by and arranged to slide vertically through plates secured to the opposite uprights B and B'. These plates, however, were not adapted to drill rods of different lengths, as they could not be adjusted towards or from each other vertically, an objection which I obviate, in the present instance, by constructing the upper guide in two pieces, *h* and *h'*, which pass partly around, and embrace the uprights, as shown in fig. 3, and which can be adjusted and secured in any position on the said uprights, according to the length of the drill-rod, by means of tightening-screws *l l*.

By means of the above improvements I increase the portability and utility of my rock-drilling machine without materially adding to its expense.

I claim as my invention, and desire to secure by Letters Patent—

1. The driving-shaft D, carrying at the opposite ends wheels F and F', and arranged on the frame of the machine, substantially as and for the purpose described.

2. The yoke G, secured to the top of the frame of the machine, for the purpose specified.

In testimony whereof, I have signed my name to this specification in the presence of two subscribing witnesses.

WM. WEILER.
